CLAIM

The ornamental design for a solar light assembly as shown and described.

DESCRIPTION

FIG. 1 is a front, top right perspective view of a solar light assembly;

FIG. 2 is a front, bottom left perspective view thereof;

FIG. 3 is a top elevational view thereof;

FIG. 4 is a bottom elevational view thereof;

FIG. 5 is a front view thereof;

FIG. 6 is a rear view thereof;

FIG. 7 is a left side view thereof;

FIG. 8 is a right side view thereof; and,

FIG. 9 is a perspective view of the solar light assembly showing environmental detail, specifically, a mounting pole. The broken lines in the drawings depict portions of the solar light assembly that form no part of the claimed design. Broken lines shown in FIG. 9 depict environmental structure which forms no part of the claimed design.

1 Claim, 5 Drawing Sheets
